FOREIGN PATENT DOCUMENTS

EM 001364293-0011 * 4/2013

Primary Examiner — Karen E. Eldridge Powers*Assistant Examiner* — Kimberly Barnes(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing my/our new design.

The broken lines showing the remainder of the display screen and the rectangle within the graphical user interface are for environmental purposes only and form no part of the claimed design.
